UNITED STATES PATENT OFFICE.

FRANK V. WIDGER, OF CHICAGO, ILLINOIS.

GEARING.

1,154,555.

Specification of Letters Patent. Patented Sept. 21, 1915.

Application filed September 27, 1912. Serial No. 722,773.

To all whom it may concern:

Be it known that I, FRANK V. WIDGER, a citizen of the United States, residing at Chicago, in the county of Cook and State of Illinois, have invented a new and useful Improvement in Gearing, of which the following is a specification.

My invention relates to apparatus for washing and wringing clothes and is accomplished by placing the clothes in a cylinder which revolves in hot water and soap, or other fluid, making one or more revolutions in one direction then automatically reversing and making one or more revolutions in the opposite direction, and so forth, and operating in conjunction with a power driven wringer through which the clothes are run ready for drying.

The objects of my invention are: to produce a power driven washing and wringing machine of the cylinder type of such construction as to eliminate to the operator the liability of accident so ordinarily involved in operating machines of this type, to minimize the amount of power required to operate the machine, to eliminate all gearing inside the body of the machine, and to provide means for automatically cleaning the inside of the body of the machine without removing the cylinder.

Another object is to provide a washing and wringing machine of the cylinder type so constructed as to bring the wringer parallel with one end of the cylinder and place it in closer proximity to the opening in the cylinder and thereby facilitate the passing of the clothes from the cylinder to the wringer and make it readily accessible from either side of the machine.

Other objects of my invention will appear hereinafter.

In the accompanying drawings Figure 1 is a front view of the mechanism, Fig. 2 is a side view, and Fig. 3 is a rear view taken at lines "A—A", Fig. 2.

Similar figures refer to similar parts throughout the several views, in which—

(4) is the body of the machine which is mounted on a frame (5). Within the body (4) is a cylinder (6) which is pivotally mounted by means of shafts (7) which are mounted in suitable bearings in the body (4), the shaft (7) which shows in Fig. 2 extending through the body (4). Rigidly mounted on the shaft (7) is a spur gear (8), (shown in dotted lines Fig. 1). Also rig-

idly mounted on the shaft (7) is a bevel gear (9). Mounted on the body (4) by means of a suitable spindle (10) is a spur gear (11) adapted to mesh with the spur gear (8). 60 Mounted on the spur gear (11) near its periphery is a lug or projection (12). Mounted on the frame (5) is a motor (13) carrying a driving shaft (14). Also mounted on the frame (5) by means of suitable bearings 65 (15) and (16) is a shaft (17). Mounted at one of its ends on the frame (5) by means of a suitable bearing (18) and at its opposite end on the body (4) by means of suitable bearings (19) and (20) is the shaft (21). 70 Rigidly mounted on the shaft (14) are the screw gears (22) and (23). Mounted at the lower end of the shaft (21) is the worm gear (24) and at the lower end of the shaft (17) a worm gear (25). The worm gear 75 (24) meshes with and is adapted to be driven by the screw gear (22) and the worm gear (25) meshes with and is adapted to be driven by the screw gear (23). Loosely mounted on the shaft (21) and adapted to 80 mesh with the bevel gear (9) are the bevel pinions (26) and (27) and which are provided with clutch jaws (45). Slidably mounted on the shaft (21) by means of a suitable key (28) is a double jaw clutch 85 (29). Pivotaly mounted on the spindle (10) by means of a suitable screw (30), or other suitable means, is a curved clutch fork (31) which is adapted to move the double clutch (29) into and out of engagement with 90 the bevel pinions (26) and (27) or to a neutral position between these two pinions as desired. Mounted on the curved clutch fork (31) in a suitable manner are the springs (53) and (54). Pivotaly mounted at one end of 95 the double clutch fork (31) in a suitable manner is an upright bar (32). Mounted on the body (4) is a projection (33) on to which is pivotally mounted a handle or hand lever (34) one end of which lever is pivotally connected to the upper end of the upright bar (32). Formed in the projection (33) are three notches (35) in which a spring operated lever or latch (36) is adapted to operate and which is attached to 100 the hand lever (34).

Rigidly mounted on the body (4) in a substantial manner is a wringer (37) of the ordinary type and having two rolls (38) and (39). The shaft (40) which passes 110 through the lower roll (39) extends beyond the frame of the wringer a sufficient dis-

tance to permit the bevel gear (41) to be rigidly mounted thereon. Loosely mounted on the shaft (17) and adapted to mesh with the bevel gear (41) are the bevel pinions 5 (42) and (43) and which are provided with clutch jaws (44). Slidably mounted on the shaft (17) by means of a suitable key is a double jaw clutch (46). The bevel gear (41), the bevel pinions (42) and (43) and 10 the double clutch (46) are inclosed in a case (47). Pivotally mounted in the case (47) in a suitable manner and adapted to engage with and operate the clutch (46) is a hand lever (48).

15 The cylinder (6) which is adapted to revolve within the body (4) is provided with an opening to which is fitted, in any suitable manner, a door (51). Built in or attached to the outer side of the door (51) in 20 any suitable manner are bristles (52), being of sufficient length to cause them to come in contact with the inside of the body (4) during part of each revolution of the cylinder (6) for the purpose of preventing any substances 25 from adhering to the inside of the body (4).

The operation of the mechanism is as follows: Motion is imparted to the shaft (14) by means of the motor (13). Through the 30 screw gear (22) and the worm gear (24) motion is imparted to the shaft (21) and the double jaw clutch (29). By throwing the spring-operated lever (36) on the hand lever (34) into the upper notch (35) on the projection (33) the clutch (29) is placed in contact with the jaws (45) on the bevel pinion (27) which causes the pinion (27) to revolve with the clutch (29) on the shaft (21) and drive the bevel gear (9) which in 35 turn causes the spur gear (8) and the cylinder (6) to revolve. Through the spur gear (8) the gear (11) is caused to revolve on its spindle. As this operation continues the lug (12) is carried around on the gear (11) 40 until it comes in contact with the spring (53). Further movement of the gear (11) causes the spring (53) to be compressed against the clutch lever (31) and which action moves the clutch (29) out of engagement 45 with the jaws (45) on the bevel pinion (27) and into engagement with the clutch jaws (45) on the bevel pinion (26). This action permits the bevel pinion (27) to run loose on the shaft (21) and the bevel gear 50 (9) is then driven in an opposite direction through the bevel pinion (26). This reversal of the direction of rotation of the bevel gear (9) also reverses the direction of travel of the spur gear (8), the shafts (7), 55 the cylinder (6) and the spur gear (11). This operation will continue until the lug (12) on the gear (11) is brought around into contact with the spring (54) on the clutch lever (31) when the action above described 60 will be repeated. The springs (53) and (54)

are of sufficient strength to throw the clutch 65 (29) into engagement with the clutch jaws (45) after it has been released by the clutch lever (31) and the lug (12). The spring 70 operated levers (36) on the hand lever (34) is of the proper tension to permit the clutch lever (31), through the bar (32) and the hand lever (34) to be moved in the notches (35). To stop the movement of the cylinder 75 (6) the operator moves the hand lever (34) up or down as the case may be, until the spring operated lever (36) rests in the central notch (35) on the projection (33). This movement, through the bar (32) and 80 the clutch lever (31) moves the clutch (29) into a neutral position between the jaws (45) on the bevel pinions (26) and (27) and the bevel gear (9), the spur gears (8) and (11), the shaft (7) and the cylinder (6) will come 85 to rest.

To operate the wringer (37) motion is imparted to the shaft (17) through the worm gear (25), the screw gear (23), the shaft (14) and the motor (13). By moving the spring operated lever (50) on the hand lever (48) into the upper notch (49) on the case (47) the clutch (46) is moved into engagement with the clutch jaws (44) on the bevel pinion (42). This causes the bevel pinion (42) to turn with the clutch (46) and drive the bevel gear (41), which in turn drives the wringer rolls (38) and (39) through the shaft (40). To reverse the operation of the wringer the spring operated lever (50) is moved to the lower notch (49). This releases the clutch (46) from engagement with the clutch jaws (44) on the bevel pinion (42) and moves it into engagement with the clutch jaws (44) on the bevel pinion (43) 95 and which drives the bevel gear (41) in the opposite direction to that described above. By moving the spring operated lever (50) into engagement with the central notch (49) the clutch (46) is held in a neutral position 100 between the clutch jaws (44) on the bevel pinions (42) and (43) and the wringer comes 105 to rest.

Having now fully described the principle of my invention and an apparatus embodying same, what I claim as new and desire to protect by Letters Patent of the United States, 115

1. In a device of the class described, the combination with a driving member, of a gear rotatable in both directions, a bevel gear connected thereto, bevel pinions freely mounted on the driving member and engaging with the beveled gear on diametrically opposite sides thereof, both of said pinions being provided with clutch teeth, a clutch member splined to the driving member and having teeth on each end adapted to engage with the teeth of the pinions, a pivoted lever to move the clutch member into engagement with the teeth of either one of 120 125 130 135 140

the pinions and into neutral position, and means carried by the said rotatable gear intermittently to engage the lever after not more than a complete rotation of the gear in either direction for moving the clutch member automatically in either direction.

2. In a device of the class described, the combination with a driving member, of a gear rotatable in both directions, a bevel gear connected thereto, bevel pinions freely mounted on the driving member and engaging with the beveled gear on diametrically opposite sides thereof, both of said pinions being provided with clutch teeth, a clutch member splined to the driving member and having teeth on each end adapted to engage with the teeth of the pinions, a pivoted lever to move the clutch member into engagement with the teeth of either one of the pinions and into neutral position, means on the rotatable gear intermittently to engage the lever for moving the clutch member automatically in either direction, and a lever for manually controlling the operation of the lever regardless of said automatic means.

3. In a device of the class described, the combination with a driving member, of a gear rotatable in both directions, a bevel gear secured thereto, bevel pinions freely mounted on the driving member and engaging with the beveled gear on diametrically opposite sides thereof, both of said pinions being provided with clutch teeth, a clutch member splined to the driving member and having teeth on each end adapted to engage with the teeth of the pinions, a pivoted lever to move the clutch member into engagement with the teeth of either one of the pinions and into neutral position, a gear meshing with the first mentioned gear having a fixed lateral projection carried thereby, and a spring mounted on each side of the lever in position to be engaged by the projection of said gear to reverse the clutch member.

4. In a device of the class described, the combination with a driving member, of a gear rotatable in both directions, a bevel gear secured thereto, bevel pinions freely mounted on the driving member and engaging with the beveled gear on diametrically opposite

sides thereof, both of said pinions being provided with clutch teeth, a clutch member splined to the driving member and having teeth on each end adapted to engage with the teeth of the pinions, a pivoted lever to move the clutch member into engagement with the teeth of either one of the pinions and into neutral position, a gear meshing with the first mentioned gear having a lateral projection carried thereby, a spring mounted on each side of the lever in position to be engaged by the projection of said gear to reverse the clutch member, and a manually operable lever in connection with the pivoted lever to move the latter and to move the clutch member independently of the automatic engagement thereof by the projection of the gear.

5. In a device of the class described, the combination with a driving member, of a gear rotatable in both directions, a bevel gear secured thereto, bevel pinions freely mounted on the driving member and engaging with the beveled gear on diametrically opposite sides thereof, both of said pinions being provided with clutch teeth, a clutch member splined to the driving member and having teeth on each end adapted to engage with the teeth of the pinions, a pivoted lever to move the clutch member into engagement with the teeth of either one of the pinions and into neutral position, a gear meshing with the first mentioned gear having a lateral projection carried thereby, a spring mounted on each side of the lever in position to be engaged by the projection of said gear to reverse the clutch member, a manually operable lever in connection with the pivoted lever to move the latter and to move the clutch member independently of the automatic engagement thereof by the projection of the gear, and means for positioning the manual lever to hold the other lever and the clutch member in neutral position or in engagement with either of the driving pinions.

FRANK V. WIDGER.
